UNITED STATES PATENT OFFICE.

GEORGE R. PIMLOTT, OF MILL VALLEY, CALIFORNIA.

LIQUID-FUEL-BURNING APPARATUS.

1,247,147.

Specification of Letters Patent. Patented Nov. 20, 1917.

Application filed January 22, 1916. Serial No. 73,609.

To all whom it may concern:

Be it known that I, GEORGE R. PIMLOTT, a citizen of the United States, residing at the town of Mill Valley, county of Marin, 5 State of California, (whose post-office address is Mill Valley), prays that Letters Patent may be granted to him for the Improvements in Liquid-Fuel-Burning Apparatus, of which the following is a specification. 10

The object of this invention is to provide a fuel oil burning apparatus in which the volume of fuel to be consumed can be automatically regulated.

15 A further object is to generally improve apparatus of this nature and render it more practical, useful, reliable and commercially desirable.

In this specification and the annexed 20 drawing, I illustrate the invention in the form I consider the best, but it is to be understood that I do not limit myself to such form, because the invention may be embodied in other forms and applied to other 25 uses, and it is also to be understood that in and by the claims following the description I desire to cover the invention in whatever form it may be embodied and applied.

In the two sheets of drawings:

30 Figure 1 is a diagrammatic side elevation of an oil-burning apparatus constructed in accordance with this invention and illustrated as applied to the fire box of a cook stove.

35 Fig. 2 is an enlarged detailed view in vertical cross-section of the fuel governing mechanism.

Fig. 3 is an enlarged detailed view of 40 the generator partly in cross section to show its external and internal contour.

Fig. 4 is a longitudinal cross section of the spray nozzle.

In detail the construction illustrated in the drawings includes the force pump 1 having the intake pipe 2, submerged in the fuel 3, contained in the reservoir 4. The reservoir may be placed in any convenient location, preferably below the circulating system so that all fuel will drain back into 45 the reservoir when the circulating system is open. The pump 1 is indicated as a gear force pump, but there are many varieties of pump equally adaptable to the purpose. The pump is driven by the gear 5 on the 50 drive shaft thereof and meshed with the pinion 6 on the shaft of the motor 7. The

fuel elevated by the pump discharges into the feed pipe 8, through the valve 9, the overflow valve 10, and returns to the reservoir through the overflow pipe 11, thus completing the circuit of the circulating system. Fuel is diverted into the burner supply system by leaving the valve 9 open, and partially closing the valve 10, restricting the flow of fuel through the circulating system 65 and diverting a portion through the governor.

The governor includes a tubular chamber 12 formed by the tube 13 having its opposite ends hermetically sealed in the heads 70 14 and 15 respectively. The head 14 has the transverse passage 16, with the by-pass 17 leading into the chamber 12, and the by-pass 18 communicating with the interior of the pressure gage 19. This gage 19 registers the pressure of the circulating system ahead of the valve 10, by which the pressure is regulated by restricting the overflow. The governor floating valve 20 is confined within the chamber 12, the upper end of 80 the float is tapered as at 21, and terminates in the spheroidal valve 22, adapted to seat against the valve seat 23 provided in the head 14 surrounding the opening 17. The lower end of the float is provided with the 85 spheroidal valve 24, seating upon the valve seat 25 surrounding the discharge opening 26, leading to the feed pipe 27 controlled by the valve 28. The float is centrally guided within the chamber 12 by the garters 29, 90 preferably formed of helical springs as illustrated and located near the top and near the bottom of the float, and adapted to engage the inner walls of the tube 13 as the float rises and falls within the chamber 12. 95 The spheroidal shape of the valves 22 and 24 cause them to hermetically engage their respective valve seats regardless of the angle that the float assumes within the tube 13. The float is provided with a small opening 100 30, through which liquid may be admitted until the float attains the same gravity as an equal volume of liquid in which it hangs suspended. This balance is most easily attained by submerging the float in the liquid 105 itself permitting the liquid to enter through the hole 30, then sealing the hole 30, when the necessary amount of liquid 31 is confined within the float, the float then having no independent tendency to rise or fall within the liquid confined within the chamber 12. 110

The fuel in the pipe 27 passes into the

generating chamber 32 of the generator, from the top of which it escapes through the return bend tube to the spray nozzle 33, illustrated in Fig. 4. Particular attention is called to the shape of the generator. The interior of the annulus takes the form of an inverted, hollow, truncated cone, having the circular opening 34 at the bottom. The interior walls converging directly from the outer rim 35 to the edge of the opening 34. The lip of the opening 34 curves outwardly and joins the outer wall 37. The outer wall extends upward parallel with the inner wall, to the junction 38 with the vertical or cylindrical wall 39 extending upward substantially parallel with the axis of the generator to the rim 36. The walls of the generator are preferably of uniform thickness, therefore the interior chamber 32 has substantially the same contour as the exterior. The lug 40 is provided to receive the return bend of the spray nozzle 33, a similar lug being provided to receive the pipe 27.

The rim 36 of the generator is provided with the annular shoulder 41, to facilitate its suspension within the bottom of the down draft tube 42 that has an inturned flange to engage the shoulder 41. The application of the down draft tube to the generator will vary according to the particular application of the generator itself. In Fig. 1 the upper annular flange 43 of the down draft tube engages a flanged opening in the top 44 of the stove.

Different makes of stoves, or different applications of a burner constructed in accordance with this invention, call for variations in structure well within the spirit of this invention.

There are instances where it is desirable to operate the tube and the generator from the horizontal plane, instead of the vertical plane as illustrated. Other occasions may require that the axis of the generator be vertical and that the axis of the down draft tube be at an angle thereto; such changes are well within the capacity of the ordinary mechanician.

The apparatus operates substantially as follows:

The fuel elevated by the pump 1 is divided by the valve 10, a portion overflowing through the pipe 11 back to the reservoir. That portion diverted by the valve 10, passes down through the chamber 12 of the governor into the pipe 27, through the valve 28 into the generator, escaping through the nozzle 33 from which it drips on to the irregular mass of fire clay, lime or other non-combustible substance, such as 45, where it is lighted by a match or torch. The float 20 having no tendency to rest heavily on the valve seat 25, under normal conditions, enough fuel will always escape to fill

the generator. To insure this the very weak spring 25' may be inserted in the opening 26, to unseat the float until the generator becomes heated.

The free burning of the fuel at the substance 45 will gradually raise the temperature of the generator subjected to the flames thereof. The quantity of fuel permitted to flow through the generator is controlled by the valve 28. The first heat of the generator tends to vaporize the fuel therein. The constantly increasing temperature of the generator raises the vapor to the form of a gas, that becomes more and more finely divided until a high state of gasification results at the point of maximum heat within the generator. This rarefied gas blows through the nozzle 33 and ignites beyond the lower opening 34 of the generator. The blast of the fuel gas escaping from the nozzle 33 at the axial center of the generator annulus and directed downwardly therethrough at a high velocity, creates an aspirating or suction effect within the down draft tube 42, carrying atmospheric air down through the tube and mixing it with the gasified fuel, which it dilutes to an enormous extent, raising the efficiency of combustion to the maximum point, below the generator. The atmospheric air rushing through the inside of the generator absorbs the heat radiated therefrom, serving the double purpose of expanding the air and maintaining a normal temperature in the generator, preventing it burning out, because of the intense heat to which its exterior walls are subjected by the flame emitted therefrom. The capacity of the generator being known, the size of the nozzle 33 is formed accordingly, within this limit the volume of atmospheric air drawn through the down draft tube automatically regulates itself, according to the volume of fuel gas emitted from the generator, whereby the manual control of the fuel regulates the flame automatically with respect to the volume of atmospheric air. The restricted nozzle outlet creates a back pressure in the generator, causing the expanding gases to force the fuel back into the pipe 27, lifting the valve 24 from its seat, if the pressure within the generator is greater than the pressure within the circulating system. If the pressure within the generator is equal to the pressure within the circulating system, the float will hang suspended between the two valve seats 23 and 25. If, however, the pressure within the generator rises above the pressure within the circulating system, the back pressure through the pipe 27 will force the float upward until the valve 22 seats hermetically against the seat 23, preventing the income of any more fuel, until the confined fuel escapes through the nozzle

and equalizes the pressure above and below the float. By this arrangement, the generator is protected against any excessive pressure that might be generated by the pump, 5 in supplying fuel faster than it could be converted at the generator. In the event of a stoppage at the nozzle, the flame would become extinguished through lack of fuel, the back pressure would be removed and the 10 float would gently close the valve 24, because of the pressure on the circulating system. Should the nozzle then open or a break occur in the pipe line 27, the pressure in this line would be removed and the pressure 15 of the circulating system on the float 20 would seat it hermetically against the valve seat 25, preventing the escape of any more fuel than that confined within the supply system below the valve 24, a quantity too 20 small to be dangerous. In the event of the stoppage of the nozzle being but momentary, the substance 45 having become incandescent in the presence of the flame, would remain hot long enough to reignite the fuel when it 25 began to flow again, thus removing the necessity of constant watching of the apparatus during its operative period.

Should the pressure in the circulating system for any reason fail, the back pressure 30 in the generator would force the float upward and hermetically close the valve 28 maintaining the pressure within the chamber 12, until the pressure within the circulating system is restored, if its stoppage was 35 but momentary or until the fuel is completely exhausted beneath the valve 22, thus maintaining the flame for a considerable period. The float 20 is extremely sensitive to pressure variations on either side, that is 40 to say, either in the circulating system or the generating system. If the main source of fuel supply fails, the governor instantly traps that fuel confined within the reservoir 45 12, supplying the generator during the emergency; on the other hand a failure in the generator causes the governor to cut off the fuel supply thereto. The pressure gage 19 registers the pressure on the circulating system and a similar gage 46 registers the pressure 50 on the generating system, giving a visual check on these respective systems.

If a normal evenly burning fire is desired, the valve 10 can be opened and the excess of fuel permitted to flow back to the reservoir. 55 On the other hand, should a demand arise for an intense fire calling for a greater volume of fuel, the valve 10 can be restricted accordingly to divert the desired quantity of fuel through the governor to the generator, the volume of flame being directly controlled by the valve 28.

It is obvious that there is no limit to size that this system of generation may be built.

By superheating a large generator commercial gas may be generated and stored instead 65 of directly consumed as illustrated; or liquids may be distilled or fractionated; or steam generated under control of this form of governor.

I claim:

1. An apparatus such as described including a reservoir; a burner connected with said reservoir; and a governor interposed between said reservoir and burner having a vertical chamber with top and bottom inlet 75 and outlet openings, and a float in said chamber having valves coöperating with said openings; said float being of substantially the same gravity as the fuel in said chamber.

2. An apparatus such as described including a reservoir; a circulating system connected with said reservoir; a pump in said circulating system; a vertical governor chamber connected with said circulating system and having top and bottom inlet and outlet openings, and a float in said chamber coöperating with said openings; and a burner connected with the outlet from said chamber.

3. An apparatus such as described including a reservoir; a circulating system connected with said reservoir; a vertical governor chamber connected with said circulating system and having top and bottom 95 inlet and outlet openings, and a float valve in said chamber of substantially the same specific gravity as the fuel passing through said chamber and coöperating with said openings, a spring means in said outlet acting against said float, a generator connected with the outlet of said chamber; and a nozzle connected with said generator and having a restricted opening.

4. An apparatus such as described including a reservoir; a circulating system connected with said reservoir; a vertical governor chamber connected with said circulating system and having top and bottom 105 inlet and outlet openings, and a float valve 110 in said chamber of substantially the same specific gravity as the fuel passing through said chamber and coöperating with said openings; a spring means in said outlet acting against said float, an annular generator 115 connected with the outlet of said chamber; and a nozzle connected with said generator having a restricted nozzle opening parallel with the axis of said generator.

In testimony whereof, I have hereunto set my hand at San Francisco, California, this 23rd day of December 1915.

GEORGE R. PIMLOTT.
